UNITED STATES PATENT OFFICE.

JAMES A. MCIVER, OF ENDERS, ARKANSAS.

PLOW.

SPECIFICATION forming part of Letters Patent No. 449,565, dated March 31, 1891.

Application filed August 25, 1890. Serial No. 363,061. (No model.)

To all whom it may concern:

Be it known that I, JAMES A. MCIVER, a citizen of the United States, residing at Enders, in the county of Faulkner and State of Arkansas, have invented certain new and useful Improvements in Plows; and I do hereby declare the following to be a full, clear, and exact description of the invention, such as will enable others skilled in the art to which it applies to make and use the same.

My invention relates to improvements in plows; and it consists in certain novel features to be hereinafter described and claimed, reference being had to the accompanying drawings, in which—

Figure 1 is a top plan view of my plow complete. Fig. 2 is a perspective view of the same with the left-hand side beam removed. Fig. 3 is a perspective view showing the right-hand beam removed. Fig. 4 shows both side beams removed, and Fig. 5 is a perspective view showing the rear section of the middle beam removed.

The same numeral references indicate corresponding parts in all the figures.

The object of my invention is to provide a combined right and left hand double-shovel plow, with the ordinary cultivator, single shovel, and the covering or cultivating double-shovel plow having its shovels directly opposite each other.

Referring to the several parts of my combined plow by their designated numerals, 1 indicates the center beam, the front end of which terminates in the usual clevis-hook 2, while to its rear end is removably secured the removable curved section 3, to the lower end of which is secured the shovel or blade 4. To the left-hand side of the front end of the beam 1 is bolted the front end of the left-hand beam 5, carrying at its rear curved end the shovel-blade 6, while to the right-hand side of the center beam 1 is bolted the front end of a right-hand beam 7, carrying at its rear end a shovel-blade 8. The side beams curve outward as they extend backward, as shown, so that their rear ends are at a suitable distance apart, the side beams being shorter than the middle beam, bringing their blades in advance of the blade of the latter.

A rod 9 passes transversely through an opening in the center beam 1, and is threaded, as

shown, and inner nuts 10 10 are screwed tight on the rod on each side of the center beam to secure the rod to this beam. The ends of 55 this threaded rod pass through openings 11 in the side beams, which are slightly larger than the rod, and the pairs of adjusting-nuts 12 13 are screwed on the ends of the rod on the outer and inner sides of the side beams, 60 as shown. The object of this arrangement is that by turning these adjusting-nuts the rear ends of one or both of the side beams can be adjusted in or out, as will be readily seen, to regulate their distance from the center beam. 65

My combined plow can be arranged and used as an ordinary cultivator, as shown in Fig. 1. By removing the left-hand side beam it can be used as a right-hand double-shovel plow, as shown in Fig. 2. By removing the 70 right-hand side beam it can be used as a left-hand double-shovel plow. When both side beams are removed, it forms an ordinary single plow, while by removing the rear section 3 of the middle beam, with its blade, the plow 75 forms a covering-plow, the opposite blades of which will run on opposite sides of and cover in the row, as will be readily seen by reference to Fig. 5 of the drawings.

To the forward end of the left-hand beam 80 is secured to the side thereof a clevis 14, to which the horse is attached when the plow is used for covering in a row, as shown in Fig. 5, this device permitting of the horse walking on the side of the row instead of on top of it. 85

When the plow is used as an ordinary cultivator, as a single plow, or as a right-hand or left-hand double-shovel plow, as shown in Figs. 1, 4, 2, and 3, respectively, the handles 15, the lower ends of which are bolted to the 90 rear part of the middle beam proper, have secured to them the upper ends of braces 16 16, the lower ends of which are bolted to the removable section 3 of the middle beam; but when this section is removed, as shown in 95 Fig. 5, to change the plow to a covering-plow, the handles are braced by braces 17 17, the lower ends of which are bolted to the side beams, as shown.

From the foregoing description, taken in 100 connection with the accompanying drawings, the construction, manner of adjusting, and advantages of my invention will be readily understood.

It will be seen that my new and improved combined plow is simple and strong in construction, and that it can be readily changed to form, practically, five different kinds of plows, and can thus be used to perform the work of five different kinds of plows.

Having thus described my invention, what I claim, and desire to secure by Letters Patent, is—

10 The combination of the center beam 1, the removable curved section 3, having an end

blade, the removable side beam 7, having an end blade, and the removable side beam 5, having an end blade and having the side clevis 14 secured to the side of its forward end, substantially as set forth.

In testimony whereof I affix my signature in presence of two witnesses.

JAMES A. McIVER.
